UNITED STATES PATENT OFFICE.

CHARLES E. GODLEY, OF DETROIT, MICHIGAN, ASSIGNOR TO THE EDMUNDS & JONES MFG. CO., OF DETROIT, MICHIGAN, A CORPORATION OF MICHIGAN.

LAMP STRUCTURE.

1,071,907.

Specification of Letters Patent. Patented Sept. 2, 1913.

Application filed September 1, 1911. Serial No. 647,156.

To all whom it may concern:

Be it known that I, CHARLES E. GODLEY, a citizen of the United States, residing at Detroit, in the county of Wayne, State of Michigan, have invented certain new and useful Improvements in Lamp Structures; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to lamp structures for vehicle lamps and consists in the formation, association, and arrangement of parts hereinafter more fully set forth and pointed out in the claims.

20 The object of the invention is to construct an oil lamp for vehicles of a pleasing design which bears no resemblance to the old lantern type of lamps, and wherein provision is made for forming the shell of the 25 lamp with a flaring portion and with a cylindrical body having two integral panels struck from the metal of the shell, one of said panels at the bottom serving as a receptacle for the oil font, and the other of 30 said panels at the top forming a ventilating hood for the lamp. The invention further 35 contemplates the employment of a shield in the rear of the lamp body to prevent the entrance of air through the openings therein through which the supporting arms enter the lamp.

The above object is attained by the structure illustrated in the accompanying drawings, in which:—

40 Figure 1 is a sectional view through the longitudinal axis of a lamp embodying my invention. Fig. 2 is a transverse section therethrough as on line 2—2 of Fig. 1. Fig. 3 is a sectional view through the shield and 45 flue carried at the upper end thereof. Fig. 4 is an elevation of the lamp. Fig. 5 is a perspective view of the shield and flue. Fig. 50 6 is a transverse section through the body and integral panels as on line 6—6 of Fig. 4, the cap being omitted.

Referring to the characters of reference, 1 designates the cylindrical portion of the body of the lamp, and 2 the front flaring portion thereof. At the bottom of the cylin-

drical portion, and extending from the rear 55 thereof forward into the flaring portion 2, is formed an integral panel 3 struck from the metal of the body and serving as a receptacle for the oil font, not shown, which may be inserted into said receptacle when 60 the door 4 is open. At the top of the cylindrical body is formed an integral panel 5 also struck from the metal thereof and serving as a ventilating hood for the lamp, said panel being provided with the side perforations 6 and with a central opening 7 at the top. To protect the interior of the lamp from the weather a cap 8 having ventilating openings therein is mounted over the opening in the hood 5. The rear end 8 of 70 the lamp is concavo-convex, and in said rear portion is adapted to be secured a fastening plate 9 to which is attached the supporting standard 10 of the lamp, said standard passing through an opening 11 in the 75 rear end 8 of the lamp. Said plate and standard are illustrated only by dotted lines in Fig. 1. Within the cylindrical portion of the lamp body at the rear is a shield 12 having a circular portion which closes the 80 rear end of the cylindrical body portion and serves as a partition between said body portion and the concavo-convex rear end 8. The shield has a straight depending portion 13 which extends into the receptacle for the 85 oil font. The presence of said shield prevents any air which may enter the aperture 11 through which the standard 10 passes entering the combustion chamber of the lamp, in such quantity as to interfere with 90 the burning thereof. At the top of the shield 12 is a perforated plate 14 projecting forwardly at right angles into the body of the lamp, said perforated plate having at its front end an upwardly extending portion 95 15 provided with an ear 16 through the medium of which it is attached to the top of the hood 5. Formed through the perforated plate 14 is a central opening around which is seated a tube 17 which serves to 100 convey the combustion vapors from the lamp, said tube being disposed directly below the opening 7 in the top of the hood. The door 4 of the lamp is provided with the usual lens or glass 18. By providing 105 the lamp body with the integral panels 3 and 5 a structure is afforded which is at once simple and compact, wherein but few

parts are used and the employment of soldered joints in the shell of the lamp is obviated.

Having thus fully set forth my invention, 5 what I claim as new and desire to secure by Letters Patent, is:—

1. A lamp casing, comprising a cylindrical shell provided with a flaring front portion, and having formed in the wall 10 thereof at the top and bottom integral panels to afford respectively an oil font receptacle and a hood for the body of the lamp, and a shield closing the rear end of the lamp body and carrying a tube at its

upper end which communicates with said 15 hood.

2. A lamp casing, comprising a shell having a rounded rear end forming a chamber, said rounded rear end of the lamp having an aperture to receive a supporting standard, 20 and a shield within the lamp body closing the inner end of said chamber.

In testimony whereof, I sign this specification in the presence of two witnesses.

CHARLES E. GODLEY.
